UNITED STATES PATENT OFFICE.

THOMAS P. SANTARELLI, OF COAL CREEK, COLORADO.

COAL-MINING SKID.

1,405,387.

Specification of Letters Patent.

Patented Jan. 31, 1922.

Application filed September 14, 1920. Serial No. 410,307.

To all whom it may concern:

Be it known that I, THOMAS P. SANTARELLI, a citizen of the United States, residing at Coal Creek, in the county of Fremont and State of Colorado, have invented certain new and useful Improvements in a Coal-Mining Skid, of which the following is a specification.

This invention relates to skids or runners 10 for coal cutting or mining machines, and has for one of its objects to improve the construction and increase the efficiency and utility of devices of this character.

Another object of the invention is to provide 15 a device of this character which may be disposed beneath the under frame of a coal cutting machine and adaptable without material structural change, to machines of various forms and sizes.

Another object of the invention is to provide 20 a device of this character whereby the coal cutting machine may be adjusted vertically, to adapt it to the vein to be cut, and to enable the course of the cutting chain to 25 be varied to avoid obstructions.

With these and other objects in view, the invention consists in certain novel features of construction as hereinafter shown and described and then specifically pointed out in 30 the claims, and in the drawings illustrative of the preferred embodiment of the invention.

Figure 1 is a plan view,

Fig. 2 is a side elevation partly in section 35 of the improved apparatus,

Fig. 3 is an enlarged sectional detail of the wedge block mechanism at the forward end of the device,

Fig. 4 is a plan view of the parts shown 40 in Fig. 3,

Fig. 5 is an end view of the parts shown in Fig. 3, with the base in section on the line 5—5 of Fig. 3.

Fig. 6 is an enlarged sectional detail of 45 the ratchet devices,

Fig. 7 is a plan view of one of the ratchet devices,

Fig. 8 is an enlarged sectional detail of 50 the wedge block mechanism at the rear end of the device,

Fig. 9 is a plan view of the parts shown in Fig. 8,

Figs. 10, 11 and 12 are details of the pull rod coupling of the rear wedge block.

The improved apparatus includes a base member in the form of a flat plate or shoe

10 curved upwardly at one end, as shown at 11, like a sled runner, to enable it to be readily drawn over the ground.

The base member 10 is provided with a 60 longitudinally directed guide way near one side edge, indicated at 12, with slightly dovetailed sides, and likewise formed with a lateral offset near one end and including the 65 curved portions 11.

The flat or horizontal part of the offset is provided with a longitudinally directed guideway, indicated at 14, and slightly dovetailed, like the guideway 12. For the purpose of the description, the curved end of 70 the plate 10 will be referred to as the front, and the opposite end as the rear.

Slidable in the guideway 12 is a bar 15 having dovetailed edges to correspond to the dovetailed walls of the guideway. By 75 this means the bar while freely movable in the guideway, will not move vertically or away from the base plate.

Formed in the bar 15 at the rear end, is a socket 16 having dovetailed ends, and bearing upon the bar is a rear wedge block 17 having a dovetailed stud 18 engaging in the 80 socket. By this means the rear wedge block is detachably coupled to the bar 15.

In its upper face the block 17 is formed 85 with a plurality of transverse half bearings to receive the journals 19 of rollers 20, the journals being held in the bearing by cap members 21 in the form of strips having half bearings to engage over the journals, 90 and held to the block by a screw between each pair of bearings.

Slidable in the shorter guideway 14 is another shorter bar or support 24, and rigidly attached to this latter bar by a plurality 95 of screws 22 is another wedge block 25 arranged reversely to the block 17.

The block 17 is therefore the "rear" block, and the block 25 is the "front" block, and are so referred to in this description.

In its upper face the front block 25 is formed with a plurality of transverse half bearings to receive the journals 26 of rollers 27, the journals being held in the bearings by cap members 28 in the form of strips 105 having half bearings to engage over the journals 26 and held to the block 25 by a screw between each pair of the bearings.

Attached across the plate 10 near the front or curved end, is a ratchet housing in channel form, which includes spaced sides 30—31, and mounted for rotation in the portion 31

are wedge block operating screws 32 and 33. The screws are provided respectively with longitudinally directed channels or grooves 34 and 35 transversely of their threads.

5 Attached to the bar 15 at the front end is a nut device 36 with which the screw engages, and attached to the side 31 of the ratchet housing is a nut device 37 with which the screw engages.

10 Engaging each of the screws 32 and 33 between the sides 30—31 of the ratchet housing are operating ratchet levers, and as the levers are alike the description of one will suffice for both.

15 Each lever comprises a hub portion 38 having ratchet teeth 39 and with a keyway to receive a key 40 engaging in the channels in the screws. By this means the hubs when rotated will correspondingly rotate the 20 screws.

25 The member 38 is formed with annular bearing flanges at the ends, and rotative upon these bearings are plates 41 each having inwardly directed guide ribs 42. Engaging the contiguous faces of the members 41 and between the ribs 42 are plates 43 connected at their outer ends to a stud 44, the latter separated from the plates 43 by a stop flange 45. The plates 43 and the members 41 30 are rigidly united by transverse pins or bolts 46 and 47.

35 Swinging upon the pins 46 side by side between the plates 43 are double toothed pawls 48, each having a divided rearward extension through which a pin 49 passes. U-shaped leaf springs 50 are disposed between the plates 43 and are formed with seats at the ends of their sides to bear respectively against the pins 46 and 49, and thus hold 40 the pawls yieldably in engagement with the ratchet teeth 39.

45 Each pawl has two teeth, and are so spaced and arranged relative to the pin 49 that the springs 50 exert their force to lock either pair of teeth in engagement with the ratchet teeth. By this means the device is reversible and can be quickly arranged to actuate the screws in either direction.

The studs 44 are designed to receive a section 50 of gas or steam pipe 51 to serve as an extension lever to actuate the ratchet.

Attached across the face of the base member 10 is a buttress device including a lower horizontal portion 52 bearing on the base and 55 an upper forwardly inclined portion 53, to limit the movement of the mining machine when supported by the wedge blocks.

50 The mining machine, represented conventionally at 54, when in its lowermost position rests by its lower member upon the plate 10 between the wedge blocks, with one side edge against the vertical portion 52 of the stop member.

65 The improved skid device is arranged cross wise of the mining machine, as shown, and

when it is required to adjust the mining machine, the ratchet levers are actuated and the screws 32 and 33 rotate to move the wedge blocks 17 or 25 in either direction upon the base member 10 and thus elevate or depress 70 the machine. If the sides of the machine are to be elevated or depressed uniformly, then both screws will be actuated in concert, or if one side of the machine is to be elevated or depressed to a greater extent than the other, this can easily be accomplished by actuating one screw to a greater extent than the other, as will be obvious.

75 Anti-friction rollers, will preferably be arranged in the lower face of the wedge 80 block 17, as shown at 55 in Fig. 2.

I claim.

1. In an apparatus of the class described, a runner member formed with longitudinally directed upwardly opening guideways in parallel relation, coacting wedge blocks movably seated respectively in said guideways, and means for independently moving said wedge blocks in the guideways to elevate or depress a structure supported 90 thereon.

2. In an apparatus of the class described, a runner member formed with longitudinally directed upwardly opening guideways in parallel relation and with overhanging 95 confronting edges, coacting wedge blocks bearing upon said runner at each side of the guideways, guide members attached to said blocks and having bevelled edges to engage the overhanging edges of the guideways, and means for independently moving said wedge blocks in the guideways.

3. In an apparatus of the class described, a runner member formed with longitudinally directed upwardly opening guideways 105 in parallel relation, coacting wedge blocks movably seated respectively in said guideways, a stop member extending transversely of the runner and with an inclined face, said stop member having an opening through 110 which one of said wedge blocks moves and operating to limit the movement of the structure supported on the wedge blocks.

4. In an apparatus of the class described, a runner member formed with longitudinally directed upwardly opening guideways in parallel relation, coacting wedge blocks movably seated respectively in said guideways, a channel member transversely of the runner, nut devices within said channel member, operating screws rotative through 120 said channel member, and respectively engaging said nuts, means for coupling said screws to said wedge blocks, and means for independently actuating said nuts to cause 125 the longitudinal movement of the wedge blocks in the guideways.

In testimony whereof, I affix my signature hereto.

T. P. SANTARELLI.
